UNITED STATES PATENT OFFICE.

LOUIS L. GORR, OF SAN JOSE, CALIFORNIA.

FLUID HEATER.

Application filed March 11, 1921. Serial No. 451,470.

To all whom it may concern:

Be it known that I, Louis L. Gorr, a citizen of the United States, residing at San Jose, in the county of Santa Clara and 5 State of California, have invented certain new and useful Improvements in a Fluid Heater; and I do hereby declare the following to be a full, clear, and exact description of the invention, such as will enable others skilled in the art to which it 10 appertains to make and use the same.

The invention aims to provide a heating apparatus generally of novel and improved construction and which attains the 15 various objects and advantages which will be pointed out and become apparent from a consideration of the description following taken in connection with accompanying drawings illustrating one practical embodiment.

In the drawings:

Figure 1 is a side view of an apparatus embodying the invention with the adjacent wall of the furnace casing in section. 25 Figure 2 is an end view of the same with the adjacent wall of the furnace casing in section.

Figure 3 is a plan view of the same.

Figure 4 is a vertical sectional view on 30 the plane indicated by the line 4-4 of Figure 2.

Figure 5 is a perspective view of one of the conductors for the fluid to be heated.

Figure 6 is a horizontal section on the 35 plane indicated by the line 6-6 of Figure 1.

Figure 7 is a vertical transverse section on the plane indicated by the line 7-7 of Figure 1.

Figure 8 is a side view of a modified construction, the walls of the furnace housing 40 being shown in section.

Figure 9 is an end view of the construction shown in Figure 8, the furnace casing being shown in section.

45 Figures 10 and 11 are vertical sectional views taken on the planes indicated respectively by the lines 10-10 and 11-11 of Figure 9.

50 Figures 12 and 13 are sectional views respectively on the planes indicated by the lines 12-12 and 13-13 of Figure 8.

55 Figures 14 and 15 are horizontal sectional views respectively on the planes indicated by the lines 14-14 and 15-15 of Figure 8.

Figure 16 is a longitudinal sectional view

of a simplified arrangement of the form illustrated in Figures 8 to 15 inclusive, and

Figure 17 is a sectional view on the line 17-17 of Figure 16.

The casing forming passages for the fluid to be heated is constructed to provide the outlet passage 20 and the inlet passage 21, arranged in the construction illustrated longitudinally of the furnace housing 23 so as to extend lengthwise through the combustion chamber 24, with the heating unit, in this instance consisting of the burner tube 25, located at the base of and under the upleg so as to cause an expansion of 70 the fluid to be heated in such relation to the body of the contents of the casing for the fluid to be heated as to produce an upward movement or circulation of the fluid through the outlet or upleg 20 with a corresponding downward circulation through the other leg to displace the expanded portion of the fluid to be heated by gravity or greater specific gravity, and in the form of the invention illustrated in Figures 1 to 80 7 inclusive, the structure embodies two units each having a U-tube or U-form casing forming passages for the fluid to be heated arranged between conductors or passages for the heating medium as shown at 26 and which are in communication with the combustion chamber and serve to convey the heat and products of combustion from the heating units to the outlet 27, the inlet and outlet openings 28 and 29 respectively for 90 the downleg and the upleg of the conductor for the fluid to be heated being arranged in juxtaposition preferably, as shown, near the front of the furnace casing.

While the outlet or upleg of the conductor for the fluid to be heated is preferably straight and vertical, the inlet or down-leg thereof is preferably of zig-zag or interrupted form, being fitted with baffle plates 30 arranged in reverse relations alternately to form staggered openings 31 and 32 located respectively near the rear and front walls of the downleg, while a corresponding reversed circuitous passage for the heating medium of products of combustion is afforded by the use of baffle plates 33 so positioned as to provide openings 34 and 35 also located respectively at the rear and at the front of the furnace to cause a progress of the heating medium in a path which is parallel with but directly opposed to that of the fluid to be heated, to the end that as

the heating medium loses its heat units in its progress from the heating unit to the outlet 27 it comes into heat communicating relation with gradually cooler volumes of 5 the fluid to be heated entering the inlet of the downleg of the conductor for said heated medium. Thus at no point in the progress of the fluid to be heated and the heating medium in traversing the oppositely directed 10 passages provided therefor, can there be a neutralization or equalization of heat units in the two mediums, and consequently no tendency to interrupt or retard the continuous uniform and active circulation in 15 opposite directions of the heating medium and fluid to be heated respectively in their progress toward the outlet 27 and the cross passage 22.

The discharge of the down-leg of the conductor for the fluid to be heated is preferably effected by means of a nozzle or extension 36 discharging in a plane adjacent to the heating unit and a considerable distance below the plane of the upper wall of the 25 combustion chamber which is represented by lateral enlargements 37 of the conductor leg 22, forming a transversely and longitudinally inclined wall 38 serving to direct the heating medium toward the inlet 39 to 30 the circuitous passage which is arranged in counter-current relation with the down-leg passage of the conductor for the fluid to be heated, and indicated by the arrows in the several figures, and obviously the discharge 35 of the down-coming column of the fluid to be heated in a plane considerably below the top of the combustion chamber defined as above described by said lateral enlargements of the casing forming the passages for the fluid to be heated will serve to prevent pocketing or stagnation of the heating medium and hence overheating of the walls of the casing. To further guard against 40 the pocketing of the products of combustion, reduced passages 40 may be provided at the extremities of the enlargements 37 to afford direct upward communication between the combustion chamber and the 45 lowermost run of the outlet passage for the products of combustion. Also in order to avoid a too intimate relation between the incoming column of fluid to be heated traversing the lowermost chamber or passage of the down-leg and the column of 50 fluid to be heated moving forward in the cross passage 22 toward the upleg of the casing, the bottom wall of the down-leg is spaced from the top wall of the cross passage 22, as shown at 41 in Figures 4 and 55 5 of the drawings. The edges of the enlargements 37 at their upper sides are flanged as indicated at 42 to provide means for conducting water of condensation to suitable drip tubes or outlets 43.

60 65 Also as a means of providing for equaliza-

tion of pressures a vent 44 is preferably provided between the upleg and down-leg passages of the conductor for the fluid to be heated near the inlet and outlet ends thereof, and obviously suitable cleaning plugs 70 45 or means for giving access to the interior of the structure at proper points to permit of removing accumulations or sediments may be provided as deemed necessary. The baffle plates in the passage for the heating medium, as indicated in Figure 2 are 75 also preferably inclined laterally to form drainage for water of condensation.

From the foregoing description of one form of apparatus embodying the principles 80 of the invention it will be seen that the counter-current passages for the fluid to be heated and the heating medium of which the former may be air or water, the latter being employed primarily as a circulating 85 medium or as the origin of steam when the latter is preferred as the circulating medium of form thereof, are so disposed as to locate the passages for the fluid to be heated between passages for the heating medium, thus 90 locating the latter exteriorly, in which event a masonry or other more or less refractory or heat non-conducting wall is preferable as an enclosing housing within 95 which is arranged a sheet metal structure constituting the U-form casing units relatively disposed as above indicated to form the conductor passages for the heating medium between said units and between the units and the side walls of the housing, as 100 clearly shown in Figure 2, and this arrangement is preferable when water is used as the fluid heating medium, or when it is desired to employ steam generated from the 105 water as the circulating medium, in which latter event however the connecting vent 44 should be made of larger dimensions than indicated in Figures 1 to 5 inclusive, and a corresponding enlargement is preferable 110 with relation to the openings connecting the runs of the passages for the heating medium in the inlet or down-leg of the U-form conductor.

When however air is to be used as the 115 fluid to be heated it is preferable under certain circumstances to dispense with the masonry housing enclosing the upper portion of the apparatus and to confine the same to the portion immediately adjacent to the combustion chamber, as in the form of the invention illustrated in Figures 8 to 15 inclusive, wherein the down-leg 50 of the conductor for the fluid to be heated is arranged exteriorly and encloses or surrounds 120 the outlet or up-leg element thereof, connected as in the construction previously described by the cross passage 52, with however the heating unit 51 located as previously described at the base of the up-leg 125 thereof, and with the conductor for the 130

heating medium enclosed or surrounded by the down-leg or inlet passage for the fluid to be heated and consisting for example of the central passage 53 which is in communication at its rear end with the combustion chamber 54 and the lateral or side passages 55 which are in communication with the central passage to afford a zig-zag or circuitous path for the products of combustion in counter or opposed relation with the path of progress of the fluid to be heated as hereinbefore described. In the construction illustrated the central passage 53 is divided to form upper and lower chambers by an interposed partition 56 and the lower chamber is in communication at its forward end by means of cross passages 57 with the lower chambers of the lateral passages 55, said lateral passages being divided into upper and lower members by partitions 58, and said lower chambers of the lateral passages being in communication by openings 59 at their rear ends with the upper chambers which in turn are in communication at their forward ends by cross passages 60 with the upper chamber of the central passage which is provided at its rear end with the smoke outlet 61. Obviously by providing the partition 56 which separates the upper and lower chambers of the passage 53 with an opening 62, (closed in the construction illustrated in Figures 8 to 15 by a cover plate 63,) direct communication between said lower and upper chambers may be afforded to convey the products of combustion to the outlet 61, in which event the lateral passages in a simplified form of the apparatus may be dispensed with. Such an arrangement is illustrated in Figures 16 and 17.

It will be seen that as in the form previously described the fluid to be heated in passing from the downleg to the cross passage is conducted by the nozzle formed by the downwardly convergent walls 64 to a plane of delivery adjacent to the bottom of the passage 52 so as to maintain an active circulation of the fluid to be heated at the bottom wall of the U-form casing which is directly exposed to the effect of the heating units, to prevent overheating thereof and insure an effective absorption of the heat units by the fluid to be heated prior to entering the up-leg or outlet passage of the conductor, and as a consequence insure an active and uniform circulation of the fluid to be heated, it being understood that the burner illustrated in the drawings as the heating unit is merely typical and is designed to represent any preferred form of heating unit adapted to utilize any suitable form of fuel.

In the form illustrated in Figures 8 to 15 inclusive the principle of operation involving the movement in opposite directions of

the heating medium and the fluid to be heated to provide against neutralization or equalization of the temperatures of the mediums at any given point is the same as previously described in connection with the 70 form of the invention illustrated in Figures 1 to 7 inclusive, and as in that form the structure illustrated in Figures 8 to 15 inclusive embodies drainage means for the water of condensation as indicated by the 75 spout 65, and the forward ends of the walls 64 are connected as indicated at 66 to insure the discharge of the downwardly moving contents of the down-leg of the casing for the fluid to be heated in proximity to 80 the bottom of the cross passage 52 before entering the lower end of the upleg. The lower wall of said cross passage is preferably arched in V-shape as indicated at 67 to increase the effect of the heating unit 85 upon the fluid to be heated and insure the raising of said fluid to the desired temperature to effect an economy in the consumption of the fuel.

In the arrangement illustrated in Figures 90 16 and 17 the casing forming the passage for the fluid to be heated is arranged exteriorly of that for the heating medium, the down-leg 70 of the former being connected with the up-leg 71 thereof by the 95 cross passage 72, with the base of the up-leg arranged adjacent to the heating unit 73, and with the circuitous passage 74 for the heating medium provided by a horizontal partition 75 having an opening 76 for establishing communication between the lower and upper chambers thereof, the lower chamber being in communication at its rear end with the combustion chamber 77 and the upper chamber having the smoke outlet 100 78 at its rear end.

As in the previously described forms the heating medium and the fluid to be heated are conducted through counter-current passages with the said mediums progressing in 110 opposite directions to provide against neutralization or equalization of the temperatures, the heating medium progressing to the outlet provided at the rear while the inlet and outlet openings of the legs of the 115 conductor for the fluid to be heated medium are disposed in juxtaposition.

Obviously, the elements of the down-leg 21 may be made separately and connected together with washers of asbestos between 120 them, the washers of asbestos preventing heat from being conducted from one element to the other.

Having thus described the invention, what I claim is:—

1. A heating apparatus having a housing, a casing within said housing, said casing including a downleg forming an inlet passage and an upleg forming an outlet passage for the fluid to be heated, said passages being 130

- in communication at their lower ends, a source of heat associated with the housing from which the heat passes upwardly from beneath the casing and along the sides thereof, said housing having an outlet at the upper part thereof.
2. A heating apparatus having a housing, a casing within said housing, said casing including a downleg forming an inlet passage and an upleg forming an outlet passage for the fluid to be heated, said passages being in communication at their lower ends, a source of heat associated with the housing from which the heat passes upwardly from beneath the casing and along the sides thereof, said housing having an outlet at the upper part thereof, and means to cause the heating medium to travel a tortuous path along the downleg of said casing to said outlet.
- 10 3. A heating apparatus having a housing, a casing within said housing, said casing including a downleg forming an inlet passage and an upleg forming an outlet passage for the fluid to be heated, said passages being in communication at their lower ends, a source of heat associated with the housing from which the heat passes upwardly from beneath the casing and along the sides thereof, said housing having an outlet at the upper part thereof, and means to cause the fluid to be heated to travel a tortuous path through the downleg of said casing.
- 20 4. A heating apparatus having a housing, a casing within said housing, said casing including a downleg forming an inlet passage and an upleg forming an outlet passage for the fluid to be heated, said passages being in communication at their lower ends, a source of heat associated with the housing from which the heat passes upwardly from beneath the casing and along the sides thereof, said housing having an outlet at the upper part thereof, and the apparatus having a vent connecting said downleg and upleg near their upper ends.
- 30 5. A heating apparatus having a housing, a sectional casing within said housing and forming a passage for the fluid to be heated, the sections of said casing consisting of a downleg, an upleg and having a cross passage forming a means of communication between said legs at their lower ends, the top of said cross passage being wider than the base; a source of heat associated with the housing from which the heat passes upwardly from beneath the casing and along the sides thereof, said housing having an outlet at the upper part of the housing.
- 40 6. A heating apparatus having a housing, a sectional casing within said housing and forming a passage for the fluid to be heated, the sections of said casing consisting of a downleg, an upleg and having a cross passage forming a means of communication between said legs at their lower ends, the top
- 50 of said cross passage being wider than the base with its upper wall inclined and having flanges at the outer edges of same to provide a drain; a source of heat associated with the housing from which the heat passes upwardly from beneath the casing and along the sides thereof, said housing having an outlet at the upper part of the housing.
- 60 7. A heating apparatus having a housing, a sectional casing within said housing and forming a passage for the fluid to be heated, the sections of said casing consisting of a downleg, an upleg and having a cross passage forming a means of communication between said legs at their lower ends, the top
- 70 of said cross passage being wider than the base, and the downleg having a nozzle extending into said cross passage; a source of heat associated with the housing from which the heat passes upwardly from beneath the casing and along the sides thereof, said housing having an outlet at the upper part of the housing.
- 80 8. A heating apparatus having a housing, a sectional casing therein forming a passage for the fluid to be heated, one of the sections of said casing embodying a hollow base having an inclined upper wall and provided at one end with an upleg or outlet passage with which it is in communication, said base being laterally enlarged adjacent said inclined upper wall, flanges at the upper longitudinal edges of said inclined wall to provide a drain; the other of said sections of the casing forming a downleg or inlet passage for the fluid to be heated and disposed opposite said upleg and over the inclined wall of the base and with its lower wall spaced above the inclined wall of the base, said downleg having a nozzle extending into said base through its upper inclined wall; baffle plates within the downleg to control the direction of flow of the incoming fluid to be heated, baffle plates exterior of the downleg to control the direction of flow of the heating medium; the apparatus having a vent connecting said inlet and outlet passages near the upper ends thereof; a source of heat associated with the housing from which the heat passes upwardly from beneath the casing and along the sides thereof, said casing having an outlet at the upper part of the housing.
- 90 9. A heating apparatus having a housing, an outer casing therein the rear of which is in spaced relation to the rear of said housing, an inner casing placed within and in spaced relation to the outer casing, a source of heat associated with the housing from which the heat passes under and to the rear of the outer casing and upwardly through the inner casing to an outlet, the fluid to be heated passing downwardly from the top of the housing along the sides of the inner casing, over the bottom of the outer casing
- 100
- 110
- 120
- 130

and upwardly along the front of the inner casing to the top of the housing.

10. A heating apparatus having a housing, an outer casing therein with downwardly and inwardly extending side walls intersecting the bottom of same, the rear of said outer casing being in spaced relation to the rear of said housing, an inner casing placed within and in spaced relation to said outer casing, and having inclined upper and lower side walls and being provided with a horizontal partition having an opening to establish communication between the lower and upper chambers formed by said partition, a 15 source of heat associated with the housing from which the heat passes under and to the rear of the outer casing and upwardly through the rear end of the lower chamber of the inner casing, to said opening between the upper and lower chambers, and through 20 the upper and lower chambers, and through the upper chamber of said inner casing to an outlet at the rear of same, the fluid to be heated passing downwardly from an opening at the top of the housing through the space between the housing and the inner 25 casing, said space forming a downleg or inlet passage, and through a cross passage formed by downwardly and inwardly extending baffles attached to the side walls of the outer casing and by the bottom and side 30 walls of said outer casing, and upwardly along the front of the inner casing through an upleg passage to an outlet at the top of the casing.

In testimony whereof I affix my signature 35 in presence of two witnesses.
